UNITED STATES PATENT OFFICE.

ORVILLE D. COTTON, OF DAYTON, OHIO.

FUEL FEEDER FOR GRATES.

Application filed July 27, 1920. Serial No. 399,259.

To all whom it may concern:

Be it known that I, ORVILLE D. COTTON, a citizen of the United States, residing in the city of Dayton, in the county of Montgomery and State of Ohio, have invented 5 certain new and useful Improvements in Fuel Feeders for Grates, of which the following is a specification.

The principal object of my invention is 10 to provide for smaller size heating units where a complete mechanical furnace is prohibitive on account of first cost, a fuel feeder which is simple and durable in construction and economical in operation. By 15 giving a continuous, even distribution of fuel over the entire grate surface, with the rate of feed being instantly adjustable from a minimum of no feed to a maximum of all that can be burned on the grate surface, my 20 coal feeder will increase both the capacity and efficiency of the heating unit and will reduce to a minimum the labor required to operate it.

My fuel feeder is particularly adapted for 25 use in laundries, school houses and other places where the initial cost of a complete mechanical furnace is prohibitive, and for manufacturing and other plants where the space available does not permit the use of 30 a mechanical furnace. It will burn the lowest grade of fuel cleanly and economically, and will comply with the most exacting smoke ordinances. Furthermore, it will increase boiler capacity, reduce maintenance 35 cost and increase boiler room efficiency.

Other important and incidental objects will be brought out in the following specification, and particularly set forth in the subjoined claims.

40 In the accompanying drawings, Figure 1 is a longitudinal sectional view of a furnace equipped with my fuel feeder. Figure 2 is a front view of the pusher box and the operating means therefor. And Figure 45 3 is a side view of the eccentric means for reciprocating the pusher box.

Throughout the specification and drawings, similar reference characters denote corresponding parts.

50 Referring to the accompanying drawings, the numeral 1 designates a 60 horse power horizontal tubular boiler mounted above a furnace 2. Secured to the furnace front above the fire door 3 is a feeder housing 4. Supported by the latter is a fuel hopper 5. Secured within the housing 4 is an in-

clined front deflector plate 6 to guide the fuel from the hopper 5 to a position in front of a pusher box 7 that is reciprocable over the flat bottom portion 8 which terminates at 60 its rear end in a concave part 9. The latter, with a concave part 10 above it, forms an opening in which rotate distributor blades 11 secured on a reel shaft 12. (See Figure 1.)

65 The fuel drops in front of the pusher box 7 by gravity, to be delivered by the latter to the distributing blades 11 which throw it upon the grate surface, their speed and angle being properly arranged to give an even distribution of the fuel over the entire grate surface.

70 The pusher box 7 is reciprocated for the above purpose by the following means. Referring to Figures 1 and 2, there are pivotally secured within recessed portions of the pusher box 7, the free ends of rocker arms 13, 13 fast on a shaft 14 journaled in bearings 15, 15 in the housing 4. Fixedly secured on one outer end of the shaft 14 is 75 a rocker arm 16 having a horizontal pin portion 17 that projects through a hole in a block 18. (See Figure 3.)

75 Projecting through a transverse hole in the bottom portion of the block 18 below the pin 17, is an eccentric rod 19 adapted to be reciprocated by an eccentric 20 on a stub shaft 21. The latter is rotated by the line shaft 22 through a sprocket chain 23 which passes around a sprocket wheel 24 on the 80 line shaft and a larger sprocket wheel 25 on the stub shaft. (See Figures 1 and 3.)

85 The block 18 is positioned for a free movement on the eccentric rod 19 between a shoulder 26 thereon and an adjusting nut 27 90 threaded on its outer end. By means of the latter the throw of the pusher box may be made instantly adjustable, for by moving the nut 27 toward the shoulder 26, the block 18 will be forced forwardly and rearwardly a 95 greater distance by the eccentric rod than when said nut is moved away from the shoulder 26. In the latter instance the rod 19 will move a greater distance through the block 18 without imparting motion to it, 100 than in the former instance. On the end of the eccentric rod 19 receiving the adjusting nut 27, a lock nut 28 is provided to maintain it in its adjusted position.

105 In operation, the fuel drops from the hopper 5, by gravity, in front of the pusher box 7 by which it is delivered to the dis-

tributing blades 11, being prevented from avalanching upon them by the rear deflector plate 29 secured within the housing 4 and inclining downwardly to a point just above the plane of movement of said pusher box. The revolving distributing blades 11, to which the fuel is delivered by the pusher box, evenly distribute it over the entire grate surface. All that is required of the operator is to supply the fuel to the hopper and by means of the nuts 27 and 28, to adjust the motion of the pusher box to feed sufficient fuel to the grate to meet the steam requirements.

15 It will thus be seen that my fuel feeder is simple and strong in construction, and as it is not exposed to the heat of the fire, there is almost no maintenance expense. In case fuel not suitable to be handled by the feeder is all that is available, or in case the feeder is for any reason out of commission, the grate may be fired by hand. This is very

convenient when, at times, it is desirable to burn refuse.

Having described my invention, I claim: 25

In a device of the type described, the combination with a fuel hopper, of a horizontally movable pusher box below said hopper, a distributing mechanism in front of said pusher box, means for reciprocating said 30 pusher box to deliver to the distributing mechanism, the fuel which descends from the hopper, and a stationary deflector plate between the distributing mechanism and the pusher box for guiding the descending fuel 35 to a place where it may be effectively pushed upon the distributing mechanism by the pusher box.

In testimony whereof I have hereunto set my hand this 23rd day of July, 1920.

ORVILLE D. COTTON.

Witness:

HOWARD S. SMITH.
